CLAIM

[21] Appl. No.: 10,870

The ornamental design for an angled bristle broom, as shown and described.

[22] Filed: Jul. 21, 1993

DESCRIPTION

[52] U.S. Cl. D4/132

FIG. 1 is a left side elevational view of the angled bristle broom; the right side being a reverse mirror view thereof; FIG. 2 is a front view of the angled bristle broom; FIG. 3 is a rear view of the angled bristle broom; FIG. 4 is a top plan view of the angled bristle broom; and, FIG. 5 is a bottom plan view of the angled bristle broom. The handle is shown broken away to indicate indeterminate length.
